J. W. COSGROVE,
SOLE HOLDER,
APPLICATION FILED FEB. 24, 1917.

1,353,892.

Patented Sept. 28, 1920.

INVENTOR.

John W. Cosgrove
By his Attorney
Nelson W. Howard

UNITED STATES PATENT OFFICE.

JOHN W. COSGROVE, OF MEDFORD, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-HOLDER.

1,353,892.

Specification of Letters Patent. Patented Sept. 28, 1920.

Application filed February 24, 1917. Serial No. 150,833.

To all whom it may concern:

Be it known that I, JOHN W. COSGROVE, a citizen of the United States, residing at Medford, in the county of Middlesex and 5 State of Massachusetts, have invented certain Improvements in Sole-Holders, of which the following description, in connection with the accompanying drawings, is a specification, like reference characters on 10 the drawings indicating like parts in the several figures.

This invention relates to holders for a pile of blanks and is herein illustrated in connection with sole holders for use in the 15 manufacture of boots and shoes.

In the manufacture of certain kinds of boots and shoes it is customary to cement a tap to a sole preparatory to sewing the two together. Commonly a pile of soles with 20 the taps freshly cemented thereto is subjected to pressure for a time sufficient for the cement to dry or set. It is desirable to provide for this operation a press and a plurality of small holders each of which 25 may be filled, placed in the press and, after having been subjected to pressure, removed therefrom and allowed to stand until the cement has set. The pressure imparted by the press should, of course, be maintained 30 by the holder.

It is an object of my invention, accordingly, to provide such holders with a simple and inexpensive but at the same time thoroughly reliable automatically operating 35 locking means by which the parts of the holders will be prevented from separating when the pressure exerted by the press is relieved, and which will maintain the holders in position to exert upon the soles therein 40 the same degree of pressure as was originally imparted thereto by the action of the press.

One feature of the present invention comprises a holder for a pile of blanks adapted 45 to be placed in and removed from a press, said holder comprising a U-shaped frame, a clamping member slideable on the arms of the U, and locking mechanism carried by said member constructed and arranged to 50 permit the member to be lowered freely but to bite the arms of the U instantly on both sides of said arms when force is applied tending to raise said member. In the illustrative embodiment of the invention

this locking mechanism consists of floating 55 levers loosely fulcrumed on the clamping member and having sharp cornered slots to receive the arms of the U, the arms being gripped by diagonally opposite corners of the slots to prevent upward movement of the member. The clamping member is thus locked firmly and instantly against upward movement until the outer ends of the levers are swung upwardly to aline the slots in the levers with the upright arms of the U-shaped frame, after which the member may be freely raised.

It is desirable that when the clamping member is raised and the levers released, the member shall remain in raised position 70 while the holder is being first emptied and then filled. Another feature of the invention consists of a holder for a pile of blanks comprising a U-shaped frame, a clamping member slideable on the arms of the U, locking mechanism comprising levers having slots to receive said arms, and yielding means for maintaining said levers in locking position whereby said clamping member will be held suspended on said arms in 75 any position to which it may be moved.

These and other features of the invention, including certain details of construction and combinations of parts, will be described in connection with an illustrative machine and 80 pointed out in the appended claims.

Referring now to the accompanying drawings,

Figure 1 is a perspective of a machine in 85 which the present invention is embodied;

Fig. 2 is a detail, principally in elevation, of a portion of the machine;

Fig. 3 shows in plan and elevation one of the locking levers, part of the lever being broken away in the elevation to show the 90 slot in cross-section, and

Fig. 4 is a perspective of a tool which 95 may be used to release the locking members.

The machine comprises a press and a unit 100 or holder which may be placed in and removed from the press. The press has a base 5 which supports a table 7 and an overhanging arm 9. In the end of the arm is a straight sided groove the open end of which is closed by a plate 11 to form a hole 105 square in cross-section to receive a plunger 13 having a rack formed on one side thereof. A shaft 15 having a hand wheel 17 at one

end and a ratchet 19 near the other end carries a pinion 21 which engages the rack to raise and lower the plunger 13. A lever 23 having a handle 25 has pivoted to it a pawl 27 which is urged at all times by a spring 29 toward a position in which the pawl engages the ratchet. When, however, the lever 23 is moved to its rearward position, as shown in Fig. 2, the tail of the pawl rides under a stationary pin 31 whereby the pawl is tilted as shown into a position in which it is out of engagement with the ratchet 19. The lever 23 is curved as shown in Fig. 1, and its hub is loosely mounted on the end 15 of the shaft 15. The table 7 of the press has formed in it a groove 33 to receive the base of a U-shaped unit or holder; and the upright portion of the frame of the press has a projection 35 formed with a similar 20 groove to receive one of the upright arms of the holder so that the holder will stand firmly in an upright position when placed in the press.

In the operation of the press the lever 23 is swung back into the position shown in Figs. 1 and 2 and the hand wheel 17 turned to raise the plunger 13 sufficiently to permit the holder with its pile of blanks to be placed upon the table 7. The hand wheel 30 17 is then turned in the opposite direction to bring the plunger down firmly upon the block or clamp, which slides on the arms of the holder, and then the lever 23 is swung forward to apply pressure to the blanks. 35 The lever is then swung back again, the plunger raised, the holder with the compressed blanks removed, and a new holder filled with uncompressed blanks placed in the press. When the plunger 13 is raised 40 it is desirable that it shall remain in raised position while the holder filled with blanks is being removed and a new one substituted. To this end a spring-pressed friction plug 37 carried by the plate 11 presses at all 45 times against one side of the plunger with sufficient force to hold the plunger in any position to which it may be moved.

The holder comprises a U-shaped frame 39 upon the arms of which a clamping block 50 41 is slidable, said block being provided with slots which fit the arms just closely enough to permit free sliding but to prevent any considerable play. Fulcrumed near the ends of the block are two locking levers 43, each 55 member, in the illustrative construction, extending into a suitable socket in the block and having at its inner end a yoke which straddles the bottom wall of the socket. These floating locking members are provided with slots 45 through which the arms 39 pass; and diagonally opposite corners, the upper ones on the inner sides of the arms 39 and the lower ones on the outer sides of said arms, are cut away or beveled 60 to form ridges, apices or corners 47, 49.

When, therefore, the locking levers are swung downwardly into the position shown best in Fig. 2, these corners are in contact with the arms 39 and any attempt to move the block 41 upwardly will cause these corners to bite the arms with a force proportional to that exerted upwardly against the block 41. If it is desired to raise said block 41, the outer ends of the locking levers must first be raised. In order to cause the locking levers to engage the arms with sufficient force to maintain the block in any position to which it may be raised, spring pressed pins 51 engage the upper sides of the locking levers. The springs 53 are sufficiently 75 strong for the purpose described but may readily be compressed by pulling up on the outer ends of the members 43.

In the operation of the machine two columns of soles with taps cemented thereto 80 are arranged, as shown in Fig. 1, with boards 55 at the top and bottom as well as intermediate the top and bottom of the columns. The clamping block 41 is then pushed down against the top board 55, and the unit or 85 holder placed in the press. The wheel 17 is then turned to bring the lower end of the plunger 13 down upon the block 43. The handle 25 is then manipulated to force the block 41 downwardly along the arms of the 90 holder 39. When sufficient pressure has been applied to the soles, the handle 25 is thrown back into the position shown, the wheel 17 manipulated to raise the plunger 13 and the 95 unit or holder removed and replaced by another. It should be particularly noted that the locking levers 43 permit downward movement of the block 41 but hold it immovably against upward movement in any 100 position to which it may be moved by the 105 plunger. In this way the pressure applied to the soles by the press is automatically maintained unchanged when the holder is removed from the press. The holder with the soles under pressure is put aside for a 110 time sufficient to permit the cement to set, after which the locking levers are loosened and the soles removed. The resiliency of the compressed soles causes the locking levers to engage the sides of the arms of the 115 holder with considerable force, so that it is not easy to lift up their outer ends and thereby release them. To facilitate this operation means is provided for lifting the outer ends of these locking levers, said means 120 being herein illustrated as a tool 57 the two arms 59 of which may be placed beneath the outer ends of the locking members 43, as illustrated in dotted lines in Fig. 1, preparatory to pressing down upon the handle of 125 the tool.

Although the invention has been set forth in connection with an illustrative machine, it should be understood that the invention is not limited in the scope of its application 130

to the particular machine which has been shown and described.

Having thus described my invention, I claim as new and desire to secure by Letters Patent of the United States:

5. A holder for a pile of blanks adapted to be placed in and removed from a press, said holder comprising a U-shaped frame, a clamping member slidable on the arms of the frame and provided with sockets, and locking levers having slots to receive the arms of the frame, the inner ends of the levers being received in the sockets.
10. A holder for a pile of blanks adapted to be placed in and removed from a press, said holder comprising a U-shaped frame, a clamping member slidable on the arms of the frame and provided with sockets in the ends thereof, and locking levers having slots to receive the arms of the frame and yokes which extend into and straddle the bottom walls of the sockets.
15. A holder for a pile of blanks, having, in combination, a U-shaped frame, a clamping member slidable on the arms of the U and provided with sockets and levers loosely fulcrumed at one end in said sockets and provided with means to receive and grip the arms of the U.
20. A holder for a pile of blanks, having, in combination, a U-shaped frame, a clamping member slidable on the arms of the U, levers loosely fulcrumed at one end on said member and having slots to receive the arms of the U, and yielding means acting to swing said levers into locking position.
- 25.
- 30.
- 35.

5. A holder for a pile of blanks adapted to be placed in and removed from a press, said holder comprising a U-shaped frame, a clamping member slidable on the arms of the frame, levers fulcrumed at one end on said member and having slots to receive the arms of the frame, and yielding means mounted on the clamping member and adapted to bear upon the levers.

6. A holder for a pile of blanks, having, in combination, a U-shaped frame, a clamping member having sockets in the ends thereof, levers fulcrumed in said sockets and having slots to receive said arms, diagonally opposite corners of said slots being cut away to form sharp apices which bite said arms on both sides when said levers are inclined in one direction, and yielding means for urging said levers to assume inclined locking positions.

7. A holder for a pile of blanks having, in combination, a U-shaped frame, a clamping block slidable on the arms of the frame, locking levers having slots to receive said arms and being fulcrumed on said block, said slots having sharp apices on opposite walls thereof, and yielding means for maintaining said locking levers in inclined position whereby said block will be held suspended on said arms in any position in which it may be placed until said locking levers are straightened.

In testimony whereof I have signed my name to this specification.

JOHN W. COSGROVE.
